[57]

The ornamental design for a phonograph or similar article, as shown and described.

DESCRIPTION

FIG. 1 is a perspective view of a phonograph showing our new design;

FIG. 2 is a top plan view, thereof; and

FIG. 3 is a right side elevational view thereof; and

FIG. 4 is a left side elevational view thereof.
The unshown rear elevational and bottom plan aspects of the claimed design are substantially flat, plain and unornamented.

*Fig. 1.**Fig. 2.**Fig. 3.**Fig. 4.*
